UNITED STATES PATENT OFFICE

ROBERT A. ILG, OF CHICAGO, ILLINOIS

FURNACE

Original application filed October 28, 1926, Serial No. 144,673. Divided and this application filed March 21, 1928. Serial No. 263,266.

This invention relates to furnaces, and the present application constitutes a division of an application heretofore filed by me on the 28th day of October, 1926, Serial No. 144,673, 5 Patent No. 1,674,828.

The furnace of the present invention employs a furnace grate of the movable endless chain type, which facilitates filling the front end of the fire chamber with coal by permitting the fire door to be located at a relatively low point and also facilitates the discharge of the ashes at the rear end of the grate by automatically dumping the same into a receptacle removable and replaceable through a door in 10 the rear wall of the furnace; and one object of the present invention is to provide improved means for actuating the endless chain grate from a point outside the furnace. Another object is to provide improved grate actuating means which will permit the grate and its support to be withdrawn through the rear of the furnace and subsequently replaced in working position without requiring any preliminary disconnecting of the grate actuating mechanism.

Other objects and attendant advantages of the invention will be apparent to persons skilled in the art as the same becomes better understood by reference to the following detailed description, taken in connection with the accompanying drawings wherein I have illustrated a practical and efficient embodiment of the principle of the invention, and in which—

Fig. 1 is a view, partly in side elevation and partly in vertical section, of my improved furnace;

Fig. 2 is a front elevation of the same;

Fig. 3 is a rear elevation thereof;

Fig. 4 is a vertical longitudinal section taken on the staggered line 4—4 of Fig. 2 parts at the front of the furnace being omitted;

Fig. 5 is a vertical transverse section taken on the line 5—5 of Fig. 1;

Fig. 6 is a vertical longitudinal section taken on the staggered line 6—6 of Fig. 2 parts at the front of the furnace being omitted.

Referring to the drawings, 10 designates

as an entirety a rectangular sheet-metal housing or casing constituting the outer shell of the furnace structure and equipped with a front wall, the upper portion 11 of which may be of sheet steel or cast iron, while the lower 55 portion 12 is preferably constructed of cast iron to support the fire and draft doors, the operating mechanism of the grate, and the cooling chamber.

Located centrally within and extending 60 lengthwise of the lower portion of the shell or casing 10 is the combustion chamber or fire box 13 of the furnace. This is a relatively narrow long structure, preferably formed with a rounded or dome-shaped top 65 as shown in Fig. 5, with its rear end registering with an opening in the rear wall of the housing normally closed by a door 14 (Fig. 3). On the bottom wall of the combustion chamber are track rails 15 accommodating 70 the wheels of a removable truck 16 on which is mounted a fuel grate 17 of the well-known endless link chain type mounted and supported on front and rear sprocket wheels 19 and 20 respectively. The grate is inclined up- 75 wardly from its forward to its rear end, the forward end being but a slight distance above the floor of the ash pit, while its rear end is sufficiently elevated to enable the ashes to be discharged into a removable ash can 21 located beneath the rear end of the grate just inside the rear door 14. This provides ample air space below the grate, and at the same time permits the front door 22 of the combustion chamber to be located at a relatively low 80 point in the front wall of the furnace, thus facilitating firing.

Attached to or cast integral with the lower portion 12 of the front wall and surrounding the opening guarded by the door 22 is a 90 hollow casting 23 adapted to contain water; the lower limb of said casting preferably extending inwardly as shown at 23' above the lower front portion of the grate and serving as a baffle to prevent the body of coal on the latter from clogging between the front wall and the front end of the grate. Water may be supplied to this jacket through a pipe 24; and, where said jacket is used as a hot water heater, the jacket may be additionally pro- 95 100

vided with an outflow pipe 25 which, with the pipe 24, may be connected into a suitable water tank. In the event that the water in the jacket 23 is used for humidifying the air, the pipe 25 may lead into one of the heated air passages of the furnace at any convenient point. This water jacket also serves to maintain a relatively low temperature of the front wall of the fire chamber, preventing waste of heat through radiation from the latter. The grate is moved to carry the body of burning coal rearwardly and upwardly from time to time as fresh firing is required by a simple foot-operated actuating mechanism herein shown as comprising a gear wheel 26 fast on the shaft of the lower grate sprocket wheel 19, a pinion 27 meshing with said gear wheel and fast on a shaft 28 journaled in the side walls of a suitable casing 29 mounted on the front wall, a ratchet wheel 30 fast on shaft 28, and a pedal lever 31 carrying a pawl 32 engaged with the ratchet wheel 30. The pedal lever 31 is depressed by the foot to actuate the grate, and is returned to normal elevated position by a pull spring 33. At the bottom of the front wall is a cleanout door 34 in which is mounted the usual draft regulator 35.

The furnace is so constructed as to provide a pair of symmetrical and relatively long passages for the flow of the hot products of combustion to the smoke flue at the top of the furnace, together with a damper-controlled by-pass which may be employed to shorten the outflow passage when firing up, or when a rapid increase in heat is desired; and also with a symmetrical pair of relatively long flow passages for the air to be heated, said air passages being so arranged that the walls of the gas and smoke passages will be efficiently bathed by the air and the heat abstracted therefrom and transmitted to the air.

Within the outer shell or housing 10 and enclosing the major portion of the top and sides of the fire box 13 is a generally rectangular inner sheet-metal hood-like structure comprising a top wall 36 spaced from the top wall of the housing 10, side walls 37 parallel with and spaced from the side walls of the housing and terminating slightly above the bottom wall of the latter, and a rear wall 38. As best shown in Figs. 4, 5 and 6, the upper portion of this hood is subdivided by suitable partitions to provide draft flues for the products of combustion and also a central vertical flue for the outflow of the heated air. 39 (Fig. 5) designates each of a pair of longitudinal partitions, and 40 and 41 (Fig. 6) a pair of transverse partitions between the longitudinal partitions 39. These partitions, with a portion of the rear wall 38 and the upper portion 11 of the front wall of the outer casing together form a central outflow passage or flue

for the heated air communicating with a flue section 42 in the top wall of the casing, to which latter is connected the warm air pipe or pipes leading to the registers. Where artificial circulation of the air is employed, an opening is provided in the upper portion of the rear wall of the outer casing, in which is mounted a frame 43 supporting an electric motor 44 operating a direct driven fan 45, which forces the return air into the space between the outer and inner casings. This air floods the space between the top walls of the casings, flows thence downwardly through the spaces between the side walls, thence upwardly between the side walls of the inner casing and the side walls of the fire box, and thence upwardly through the warm air flue formed by the partitions 39, 40 and 41, the rear wall 38 of the inner casing and the front wall 11 of the outer casing.

Between the longitudinal partitions 39 and extending from the lower edge of the transverse partition 40 to the rear wall 38 is a horizontal plate 46 (Fig. 6); and similarly positioned between the longitudinal partitions 39 and extending from the upper edge of the transverse partition 41 to the rear wall 38 is a horizontal plate 47. These plates are apertured, and fitted between them is a short by-pass flue section 49. The upper and lower rectangular chambers thus formed communicate through upper and lower ports 50 and 51 respectively with longitudinally extending side flues formed between the longitudinal partitions 39 and the side walls 37 of the hood. The bottoms of these side flues are closed by horizontal plates 52; and the rear bottom and top portions of the space between said side flues are closed by a horizontal plate 53 and the central longitudinal portion of the top wall 36, the former of which is apertured to receive the upper end of a short flue section 55 mounted on and communicating with the combustion chamber 13, while the latter is apertured to receive a smoke discharge flue 56. Attached to the rear wall of each of the side flues between the upper and lower ports 50 and 51 is a longitudinally extending baffle plate 57 that is preferably forwardly and downwardly inclined, as shown in Fig. 4; and within the flue section 49 is a pivoted damper 58 mounted on an operating rod 59 extending through the front wall of the furnace. The outer surfaces of the side walls 37 of the hood are preferably equipped with heat radiating fins 60. On the front wall of the outer casing are cleanout doors 61 normally closing the front ends of the side smoke flues.

Where the fan 45 is employed to create an artificial circulation of the air, it may be located, as shown in Fig. 1, within the cold air return flue 62 which ordinarily communicates with a grating in the floor of the room above the furnace. Fresh air may be

permitted to the extent desired by providing on the side of the flue 62 an opening guarded by a pivoted wing valve or damper 63 which may be closed or opened more or less by a rod 64 which may extend to the room above. Automatic regulation of the temperature may, manifestly, be effected by actuating the valve 63 by a thermostat; said valve thus serving not only to admit fresh air when desired, but also, when thermostatically controlled, as an automatic temperature regulator.

The operation and advantages of the described furnace will it is believed be clear from the foregoing description of its structural features. The inclined chain grate provides increased space at the forward portion of the fire box for firing and makes it easy to fill the front portion of the grate with coal, since it permits the fire door to be located much closer to the floor line. The elevation of the rear end of the grate provides ample space for the location therebeneath of an ash receptacle for catching all of the spent material, reducing the frequency with which the finer portions of the ashes falling beneath the grate have to be removed. And the mounting of the grate on a truck bodily removable through a door opening in the rear wall of the furnace greatly facilitates cleaning, repairs and renewals when required and automatically brings the grate-actuating gears 26 and 27 into register when the grate is fully entered.

The provision of the water jacket around the fire door and above the lower end of the grate is valuable as maintaining an even temperature in the front of the fire chamber and a lower temperature at the point where the new fuel is supplied through the fire door. This feature also performs the function of the usual hot water coil in supplying hot water for any purpose, while it may also, be used for humidifying the air passing through the furnace. In lieu of employing water in the jacket for the purposes above-mentioned, the outlet pipe 25 may be left open, and the inlet pipe 24 may be connected to the rear part of the furnace where fresh air is introduced by the fan, creating a plenum condition. This will provide a natural cool air circulation which will function the same as the water in keeping down the temperature at the front of the fire chamber.

The cool air, whether forced in by the fan, or flowing in by gravity, flows over the top and sides of the inner shell, below the lower edges of the side walls of the latter, thence upwardly between said side walls and the sides and top of the fire chamber, and thence upwardly through the relatively large central air flue. With the damper 58 closed, smoke and hot gases of combustion flow from the fire box through the short neck 55, thence through the lower ports 51 into the two side

flues below the baffles 57, flowing forwardly beneath the latter, thence around their front ends, thence rearwardly through the upper portions of the side flues, thence through the upper ports 50 into the discharge flue 56. 70 The walls 36 and 37 of the inner shell thus become highly heated through direct contact with the hot gases, and, since these walls are bathed by the air flowing through the furnace, a very efficient heat exchange is effected. 75

The use of thin sheet-metal in the greater portion of the furnace structure lends itself to economy in production and superior efficiency in heat exchange; and where employed in connection with artificial air circulation, as shown, increases the rapidity with which the rooms served by the furnace can be brought to a desired temperature. 80

While I have shown and described my present improvements in association with a furnace of the hot air type which includes a heat exchange feature above the fire box, it is to be understood that the present improvements relate to the fire box and grate 90 structure and are applicable to other types of furnaces, such as those used in hot water and steam heating plants.

While I have herein shown and described one practical and efficient embodiment of the principle of the invention, it is manifest that minor details of structure and arrangement may be resorted to without departing from the principle of the invention or sacrificing any of the benefits or advantages thereof. 100 Hence, I do not limit the invention to the exact construction shown and described for purposes of illustration, but reserve all such variations, modifications and mechanical equivalents as fall within the spirit and purview of the claims. 105

I claim:—

1. In a furnace, the combination with a combustion chamber having an opening in its rear wall, of track rails on the bottom 110 of said chamber, a truck movable into and out of said chamber through said opening, on said rails, an upwardly and rearwardly inclined endless chain grate mounted on said truck, a door closing said opening, and gearing for actuating said grate mounted partly on the latter and partly on the front wall of said combustion chamber and adapted to be automatically coupled when said grate is fully entered into said combustion chamber. 115

2. In a furnace, the combination with a combustion chamber having an opening in its rear wall, of a frame in said chamber, front and rear shafts journaled in said frame, sprocket wheels on said shafts, an endless chain grate mounted on said sprocket wheels, a gear fast on said front shaft, a shaft journaled on the front wall of said combustion chamber, a pinion fast on said last-named shaft meshing with said gear, a ratchet on 125

said last-named shaft, a lever pivoted on said last-named shaft and carrying a pawl co-operating with said ratchet, and a spring for effecting the idle movement of said lever.

5 3. In a furnace, the combination with a combustion chamber having an opening in its rear wall, a truck movable into and out of said chamber through said opening, front and rear shafts journaled in said truck, 10 sprocket wheels on said shafts, an endless chain grate mounted on said sprocket wheels, a gear fast on said front shaft, a shaft journaled on the front wall of said combustion chamber, a pinion fast on said last-named 15 shafts, means for turning said pinion, and track rails on the bottom of said combustion chamber for guiding said truck into the latter and bringing said gear and pinion into mesh.

20 4. In a furnace, the combination with a combustion chamber having an opening in its rear wall, of a truck movable into and out of said chamber through said opening, an upwardly and rearwardly inclined endless 25 chain grate mounted on said truck, a door closing said opening, and a removable ash receptacle located below the elevated rear end of said grate.
